[57] ABSTRACT

A process for controlling fungi and bacteria with com-

in which X is chlorine or bromine, R is hydrogen or alkyl having from one to six carbon atoms; R¹ is alkyl having one to four carbon atoms, or haloalkyl having one to four carbon atoms; phenyl, or nuclear substituted derivatives thereof in which the substituents are halogen, nitro or lower alkyl; R² is alkyl having from one to six carbon atoms; haloalkyl having from one to six carbon atoms; alkenyl having from two to four carbon atoms; and —NHR₃ in which R₃ is alkyl having from one to eight carbon atoms; halomethyl; phenyl and nuclear substituted derivatives thereof in which said substituents are halogen or nitro; and alkenyl having from two to four carbon atoms.

11 Claims, No Drawings

CONTROLLING FUNGI AND BACTERIA WITH CERTAIN OXIME ESTERS

This application is a division of application Ser. No. 52,769, filed July 6, 1970, which is a continuation-in-part of application Ser. No. 879,967 filed Dec. 4, 1969, which is a divisional of application Ser. No. 649,024, filed June 26, 1967, all abandoned.

This invention relates to the use of certain keto oxime esters in controlling fungi and bacteria.

The compounds useful in the process of the present invention are those having the formula

in which X is chlorine or bromine, preferably chlorine; R is hydrogen or alkyl having from one to six carbon atoms, preferably hydrogen; R¹ is alkyl having one to four carbon atoms, haloalkyl having from one to four carbon atoms, phenyl, or nuclear substituted derivatives thereof in which the substituents are halogen, nitro, and lower alkyl, preferably chloromethyl; R² is alkyl having from one to six carbon atoms; haloalkyl having from one to six carbon atoms, preferably halo-methyl; alkenyl having from two to four carbon atoms; —NHR₃ in which R₃ is alkyl having from one to eight carbon atoms, preferably methyl; halomethyl; phenyl, and nuclear substituted derivatives thereof in which said substituents are nitro or halogen, preferably 4-chlorophenyl and alkenyl having from two to four carbon atoms; most preferably, R₂ is alkenyl having two to four carbon atoms.

The compounds useful in the process of the present invention can be prepared by reacting a compound of the formula

in which X, R and R¹ are as defined with a compound of the formula

in which halo is chlorine or bromine and R² is as defined.

Preferably, the reaction is carried out in the presence of a base such as pyridine and in a solvent for the reactants. Generally, the reaction is exothermic so no heating is required. Cooling is sometimes required to control the reaction rate. The compounds of this invention can be recovered from the mixture and purified by standard procedures.

Compounds of the formula

5 can be prepared by reacting

10 with excess hydroxylamine hydrochloride or hydroxylamine hydrobromide in ethanol and water, wherein X, R, and R¹ are as defined. The reaction can be run with heating under reflux for several hours. The desired 15 product is recovered and purified by conventional techniques.

Preparation of the compounds useful in the practice of the process of this invention is illustrated by the following examples.

20 EXAMPLE 1 — 1,3-dichloroacetoneoxime

63.5 gms. (0.50 moles) 1,3-dichloropropanone, 69.5 gms. (1.00 moles) hydroxylamine hydrochloride, 250 ml. ethanol and 25 ml. of water were combined and heated under reflux for 4 hours. The cooled mixture was poured into 500 ml. of water. The aqueous solution was extracted with 3 100 ml. portions of chloroform. The chloroform phases were combined and dried with anhydrous MgSO₄. The chloroform was evaporated to 30 give 66.3 g. (93.6% of theory) of 1,3-dichloroacetoneoxime,

N_D³⁰ = 1.5044.

EXAMPLE 2 — 1,3-dichloroacetoneoxime trichloroacetate

7.1 gms. (0.05 moles) 1,3-dichloroacetoneoxime, 9.1 gms. (0.05 moles) trichloroacetyl chloride and 100 ml. benzene were added to a 500 ml. flask, stirred and cooled to 10°C. with an ice bath. 4.7 gms. (0.06 moles) 45 pyridine was added at a rate sufficient to maintain the reaction temperature below 20°C. After the addition of the pyridine, the ice bath was removed, and the mixture was stirred at room temperature for 1 hour. An additional 100 ml. benzene was added, and the mixture was washed with 50 ml. dilute HCl followed by two 100 ml. water washes. The benzene phase was dried with MgSO₄ and evaporated to give 10.4 gms. 1,3-dichloroacetoneoxime trichloroacetate

55

N_D³⁰ = 1.5078.

EXAMPLE 3 — 1,3-dichloroacetoneoximino N-allylcarbamate

11.7 gms. (0.08 moles) of the 1,3-dichloroacetoneoxime and 6.7 gms. (0.08 moles) of allylisocyanate were combined in 100 ml. of benzene. After the exothermic reaction had subsided, the mix-

ture was washed with 2 50ml. portions of water. The benzene phase was dried with anhydrous $MgSO_4$ and evaporated to give 12.2 g. (72.8% of theory) of 1,3-dichloroacetoneoximino-N'-allylcarbamate

$N_D^{30} = 1.5100$.

EXAMPLE 4 — 1,3-dichloroacetoneoximecrotonate

10.0 gms (0.07 moles) 1,3-dichloroacetoneoxime, 7.2 gms. (0.07 moles) crotonyl chloride were combined in 100 ml. of benzene. The mixture was stirred and cooled to 10°C. 6.3 gms. (0.08 moles) of pyridine was added over a period of 15 minutes. The mixture was stirred at room temperature for 1 hour. An additional 100 ml. benzene was added and the mixture was washed with two 100 ml. portions of water. The benzene phase was dried with anhydrous $MgSO_4$ and evaporated to give 8.3 g. (55.8% of theory) of 1,3-dichloroacetoneoximino crotonate

$N_D^{30} = 1.5090$.

EXAMPLE 5 —

1,3-dichloroacetoneoxime-N'-methylcarbamate

14.2 gms. (0.1 moles) of 1,3-dichloroacetoneoxime was dissolved in 50 ml. chloroform and was cooled to 10°C. in an icebath. 11.4 gms. (0.2 moles) of allylisocyanate was added at a temperature between 10° and 35°C. After the addition, the mixture was vacuum stripped. The resulting oil was dissolved in 150 ml. benzene and washed with two 100 ml. portions of water. The benzene phase was dried with anhydrous $MgSO_4$ and evaporated to give 13.7 gms. (68.9% yield) of 1,3-dichloroacetoneoxime N'-methylcarbamate,

$N_D^{30} = 1.5062$.

EXAMPLE 6 —

1,3-dichloroacetoneoxime-N'-(4-chlorophenyl) carbamate

7.1 gms. (0.05 moles) 1,3-dichloroacetoneoxime, 7.7 gms. (0.05 moles) 4-chlorophenyl isocyanate, and 50 ml. acetone were combined in a 250 ml. flask. The resulting mixture was stirred at room temperature for 1 hour, poured into 200 ml. benzene, and washed with two 100 ml. portions of water. The benzene phase was then dried with $MgSO_4$ and evaporated to yield 13.5 gms. of 1,3-dichloroacetoneoxime-N'-(4-chlorophenyl) carbamate.

EXAMPLE 7 — 1,4'-dibromoacetophenone oxime-N'-methyl carbamate

1,4'-dibromoacetophenone, 1-bromo was reacted with hydroxylamine hydrochloride to produce 1,4'-dibromoacetophenoneoxime in the manner described in Example 1 for the preparation of 1,1-dichloroacetoneoxime. The oxime was reacted with methylisocyanate, and the product was isolated in the manner described in Example 1 for the preparation of 1,1-dichloroacetoneoxime N'-allylcarbamate to yield the desired product having the following structural formula:

m.p. 139°-143°C.

The following is a table of certain selected compounds that have been prepared according to the procedure described hereto. Compound numbers have been assigned to each compound and are used throughout the remainder of the application.

TABLE I

COM- POUND NO.	X	R	R ¹	R ²
1 ^a	Cl	hydrogen	chloromethyl	-NH-methyl
2 ^b	Cl	hydrogen	chloromethyl	-NH-allyl
3	Cl	hydrogen	chloromethyl	-NH-isopropyl

In Vitro Vial Test

The following test illustrates utility of the compounds in controlling fungi and bacteria. This test measures the bactericidal and fungicidal properties of a compound when in contact with a growing bacterium or fungus. The test is conducted by partially filling two 1-ounce vials with malt broth and one 1-ounce vial with nutrient broth. Next the test compound is added to the vials at a certain concentration, expressed in parts per million, and mixed with the broth. A water suspension of spores of the desired fungi or cells of the desired bacteria (one organism per vial) is added. The vials are then sealed and incubated for one week; at this time the vials are examined and the results recorded. Table IV shows the results of various compounds tested by the in vitro vial test.

TABLE IV

27		>50	25	>50	>50

As can be seen by the test results, the compounds find particular utility as bactericides and fungicides. The compounds can be applied in a variety of ways at various concentrations. They can be combined with suitable carriers and applied as dusts, sprays, or drenches. The amount applied will depend on the nature of 50 the utility. The rate of application can also vary with the microbiological use intended.

It is claimed:

1. The method of inhibiting the growth of fungi which 55 comprises applying thereto a fungicidally effective amount of the compound having the formula

2. The method of inhibiting the growth of fungi which 65 comprises applying thereto a fungicidally effective amount of the compound having the formula

3. The method of inhibiting the growth of fungi which comprises applying thereto a fungicidally effective amount of the compound having the formula

4. The method of inhibiting the growth of fungi which comprises applying thereto a fungicidally effective amount of the compound having the formula

5. The method of inhibiting the growth of fungi which comprises applying thereto a fungicidally effective amount of the compound having the formula

6. The method of inhibiting the growth of fungi which comprises applying thereto a fungicidally effective amount of the compound having the formula

7. The method of inhibiting the growth of fungi which comprises applying thereto a fungicidally effective amount of the compound having the formula

8. The method of inhibiting the growth of fungi which comprises applying thereto a fungicidally effective amount of the compound having the formula

9. The method of inhibiting the growth of bacteria which comprises applying thereto a bacterically effective amount of a compound of the formula

10. The method of inhibiting the growth of bacteria which comprises applying thereto a bacterically effective amount of a compound of the formula

11. The method of inhibiting the growth of bacteria which comprises applying thereto a bacterically effective amount of a compound of the formula
